(57) **CLAIM**

The ornamental design for package for medication, as shown and described.

DESCRIPTION

FIG. 1 is a top perspective view of a package for medication in a closed position, showing my new design;

FIG. 2 is a left side elevational view thereof;

FIG. 3 is a right side elevational view thereof;

FIG. 4 is a front end elevational view thereof;

FIG. 5 is a rear end elevational view thereof;

FIG. 6 is a top plan view thereof;

FIG. 7 is a bottom plan view thereof;

FIG. 8 is a bottom perspective view thereof;

FIG. 9 is a top perspective view thereof in a first open position;

FIG. 10 is a top perspective view thereof in a second open position; and,

FIG. 11 is a top perspective view thereof in a third open position.

The broken lines in the Figures illustrate environmental features and form no part of the claimed design.

The shading lines in the figures illustrate contours only, not surface ornamentation, and form no part of the claimed design.
